UNITED STATES PATENT OFFICE.

CHARLES H. ANDERSON, OF CINCINNATI, OHIO.

FLOOR CONSTRUCTION FOR PASSENGER-CARS.

1,244,824.

Specification of Letters Patent. Patented Oct. 30, 1917.

Application filed August 6, 1915. Serial No. 44,068.

To all whom it may concern:

Be it known that I, CHARLES H. ANDERSON, a citizen of the United States, and a resident of Cincinnati, in the county of Hamilton and State of Ohio, have invented 5 certain new and useful Improvements in Floor Construction for Passenger-Cars, and I do hereby declare the following to be a full, clear, and exact description of the invention, such as will enable others skilled in the art to which it appertains to make and use the same.

My invention relates to an improvement in floor construction for passenger cars, and 15 particularly street cars.

With cars having steel floors composed of plates supported on and riveted to cross bearers, considerable trouble is experienced and expense occasioned by reason of the uneven surface. It is practically impossible to 20 make the plates lie perfectly flat, and the rivets projecting above the plates at the joints, cause expense in fitting the covering used for the floors. If wood is used as a 25 covering, recesses must be cut in the underside of the planks wherever rivets project, and the same is also true when a cork covering is used. Again, with cork covering it is difficult and expensive to properly fit the 30 cork over the joints in the plates.

The object of the present invention is to dispense with the ordinary cross bearers used in car floor construction and so construct the steel floor plates that they will be 35 sufficiently rigid to support the loads and at the same time obtain a smooth upper surface without joints or exposed rivets; and it consists in the construction and arrangement of parts as will be more fully explained and 40 pointed out in the claims.

In the accompanying drawings, Figure 1 is a view of a part of a car floor embodying my invention; Fig. 2 is a view of a part of one of the end platforms of the car. Figs. 45 3 and 4 are modifications of the construction shown in Fig. 1 and Fig. 5 is a view of one end of one of the longitudinal plates 6^a shown in Fig. 4.

6 represents steel floor plates, the side 50 edges of which are bent into L-shape, so that when the plates are assembled, the horizontal member 7 of one side edge will overlap the horizontal member 8 of the bent side edge of the next plate 6 and form U- 55 shape depending channeled projections, which extend transversely of the car and act

as cross bearers and stiffening members for the plates 6. The overlapping edges 7 and 8 of the plates are secured together by rivets 9, which as shown, are located at the bottoms 60 of the channels, thus leaving the upper surfaces of the plates flat and free from obstructions, and permitting the wood or other floor 10 to be placed in position and lie flat on the steel floor plates without any preliminary recessing for projecting rivets, or 65 trimming to accommodate projections at the joints. The wood or other covering is secured to the floor plates by screws 11 put in from the underside.

If desired the plates 6 may be lightened considerably by punching holes therein as shown in Fig. 3, the holes being at regular or irregular intervals apart and of the same or different sizes.

In Fig. 4 I have shown the plates 6 having depending channeled projections running crosswise the car, as in Fig. 1, secured to plates having depending channeled projections running lengthwise as in Fig. 2. It 80 is sometimes necessary to do this at points over the motors and wheels when the latter in pivoting would come in contact with the channels. In this form the plates 6^a are identical in construction with the plates 6 85 as previously described except that the channels formed at the edges of said plates extend longitudinally the car instead of transversely as in Fig. 1, and when the two forms are combined in one floor, the edges of plates 90 6 adjacent the plates 6^a, are bent into L-shape, the horizontal members 13 of the L-shaped ends resting under and forming supports for the channeled projection of the plates 6^a, the adjacent end of the plate 6 being reinforced and strengthened by the reinforcing channel bar 14.

The ends of the plates 6^a at the channeled projection, are cut away as shown in Fig. 5, the projecting end 100 webs 15 formed by cutting away the corners of the plate 6^a, being bent downwardly and resting against the outer face of the vertical members of bent end 13 of plate 6. After the parts have been thus assembled, 105 they are secured by rivets 16 passing through the bottoms of the channels of the plates 6^a and through the horizontal members of the bent ends of plate 6, and also by the rivets 17 passing through the depending end webs 15 of plate 6^a, the vertical member of the 110 bent ends of plates 6 and the reinforcing channel bar 14 under plates 6,

The end platforms of the car are also preferably constructed with the channels running lengthwise the car as in Fig. 2, and the ends are finished by the channel bar 18 secured by rivets 9 to the bases of the channels in plates 6^a and to the plates intermediate the channels by the rivets 20. The channel bar 18 extends the width of the car, and may be straight or curved and 10 form the bumpers at the ends of the car. The end platform, shown in Fig. 2, may be secured to the main floor section of the car shown in Fig. 1, in the same manner that the sections 6^a and 6 are connected in Fig. 4. 15 By riveting the bottom members of the channeled projections in plate 6^a to the bottom flange of the bumper channel bar 18, and the plate 6^a at points between the channels to the top flange of the said bar 18, I 20 secure a substantial end construction so that any blow that the car may receive will be transmitted to the steel plates 6^a and 6 which being more or less yielding will give and thus prevent any material damage except 25 from a very heavy blow.

By providing the floor plates with depending channeled projections they will be self sustaining without the use of cross bearers, and by forming the channels at the 30 junctures of the plates, the latter can be secured together in a plane below the floor proper, thus leaving the latter free from any projections which would interfere with or necessitate recessing or trimming the 35 floor covering.

It is evident that many slight changes might be resorted to in the relative arrangement of parts shown and described without departing from the spirit and scope of my 40 invention. Hence I would have it understood that I do not wish to confine myself to the exact construction and arrangement of parts shown and described but

Having fully described my invention what 45 I claim as new and desire to secure by Letters-Patent, is:—

1. A floor for cars consisting of metal plates each bent downwardly and outwardly at its side edges, the outwardly projecting 50 portions of the depending members overlapping and securing means uniting said overlapping members, the said downwardly and outwardly projecting members forming channeled projecting members extending 55 transversely of the car floor and open at the top.

2. A floor for cars consisting of metal

plates having downwardly and outwardly bent edges, an outwardly bent edge of one plate overlapping an outwardly bent edge 60 of the next adjacent plate and forming a depending projection open at the top and extending transversely of the car floor, securing means uniting the overlapping members of said projections and a floor cover- 65 ing resting on the plates.

3. A floor for cars consisting of metal plates having downwardly and outwardly bent side edges, an outwardly bent edge of one plate overlapping an outwardly bent 70 edge of the other plate and forming a channel open at the top and extending transversely of the car floor, securing means uniting said overlapping members of the channel, a floor covering resting on the 75 plates and securing means passing up through the plates and into the said covering.

4. A floor for a car composed of connected plates having depressions forming channels 80 extending transversely of the car floor, and other plates having similar channels extending lengthwise the floor, the two sets of plates being connected.

5. A steel floor for cars composed of metal 85 plates having bent edges, the bent edges of two adjacent plates forming a channel open at the top, the channels of some of the plates extending transversely of the car floor, and the channels of other plates extending longitudinally of the floor, and a floor covering 90 for the said plates.

6. A floor for cars composed of steel plates having channeled projections extending 95 lengthwise the car floor, and a U-shaped channel bar secured to and covering the outer ends of the plate and forming the car bumper.

7. A floor for cars composed of steel plates having channeled projections extending 100 lengthwise the car floor, and a channel bar covering the ends of the plates and forming the car bumper, the lower flange of said bar being riveted to the lower chords of the channeled projections and the upper flanges 105 being riveted to the plates intermediate said channeled projections.

In testimony whereof, I have signed this specification in the presence of two subscribing witnesses.

CHARLES H. ANDERSON.
